UNITED STATES PATENT OFFICE.

JOHN F. FARRINGTON, OF FLUSHING, NEW YORK, ASSIGNOR, BY MESNE ASSIGNMENTS, TO WESTERN ELECTRIC COMPANY, INCORPORATED, A CORPORATION OF NEW YORK.

RADIO SIGNALING SYSTEM.

Application filed April 22, 1925. Serial No. 24,916.

This invention relates to signaling systems and more particularly to an oscillation generator adapted to operate at substantially constant frequency.

5 An object of this invention is to prevent changes in load impedance from reacting upon the frequency determining circuit of an oscillation generator.

Another object is to provide an oscillation 10 generator capable of producing oscillations of substantially constant frequency.

A feature of the invention is the use of the frequency determining circuit of an oscillator tube as the coupling circuit for an amplifier.

15 These objects and others which will be apparent as the nature of the invention is disclosed, are accomplished in a circuit including an oscillating vacuum tube and an amplifier by employing a balancing condenser 20 forming one branch of a Wheatstone bridge, the other branches of which include the internal capacity of the amplifying tube and the impedances of the frequency determining circuit of the oscillator.

25 Although the novel features which are believed to be characteristic of this invention will be pointed out more particularly in the claims appended hereto, the invention itself, its object and advantages, the manner of its 30 organization and the method of its operation will be better understood by referring to the following specification taken in connection with the accompanying drawing forming a part thereof in which Fig. 1 is a diagrammatic representation of a radio signaling system embodying this invention; and Fig. 2 shows a modification of the portion of Fig. 1 at the left of the line 2-2.

35 In Fig. 1 is shown an oscillation generator 40 1, therein represented as a three-electrode space discharge device although any other suitable means for producing high frequency oscillations may be employed, the frequency of which is determined by an oscillatory circuit comprising inductances 3 and 4 connected in the plate and grid circuits respectively and condenser 2 connected across the two inductances. Inductances 3 and 4 are 45 preferably magnetically coupled together although it is not essential to the operation of this invention that there be coupling between these elements. Space current for the tube is supplied by source 5. Condenser 6

is used to form a shunt to source 5 for high frequency oscillations.

55 The oscillations produced in the above described system are impressed upon the grid filament circuit of space discharge amplifier 7 by means of inductance 4. The output circuit of the amplifier is connected to a 60 variable impedance load L which may be an antenna circuit, a bank of amplifiers or any other suitable circuit the impedance of which may be subject to variations. Space current is supplied to tube 7 by source 8. Balancing 65 condenser 9, the operation of which will be hereinafter set forth, is connected between the anode of the tube 7 and terminal 12 of inductance 3. Capacity 10 represents the 70 grid plate capacity of tube 7 and such additional capacity as is inherent in the socket and connections associated therewith. The capacity 10 may be increased by the addition of a fixed condenser if desired.

75 In the modification shown in Fig. 2 the capacitative and inductive branches of the oscillating circuit are interchanged. Condensers 13 and 14 and inductance 15 constitute the frequency determining elements. The value of the inductance or the capacity 80 of the condensers may be varied to alter the frequency. Plate potential is supplied from source 5 through radio frequency choke coil 16. Grid biasing potential is obtained for tube 1 by grid leak resistance 17 and condenser 18, and for tube 7 by battery 19. Choke coils 20 and 21 prevent radio frequency electro-motive forces from being applied to the sources 17 and 19 respectively which would tend to short-circuit condenser 14.

85 Although the above two types of oscillation generators have been specifically described any other suitable type of circuit may be employed and the balance hereinafter described used therewith if desired.

95 Variations in impedance of load L will change the input impedance of amplifier 7 due to the internal grid-plate capacity of tube 7 which couples the load circuit to the 100 input circuit. Amplifier 7 being connected in parallel with inductance 4 of the oscillating circuit of tube 1 will vary the impedance of that circuit whenever the input impedance of the amplifier tube is changed. Inasmuch 105 as the frequency of the oscillations produced

by source 1 is determined by the electrical constants of the oscillating circuit, any variation in impedance of the elements of this circuit will produce a change of frequency of the oscillations generated by source 1.

Such variation in frequency is prevented from taking place however, by condenser 9 which is connected as described above between the anode of tube 7 and a point in the 10 oscillating circuit the high frequency potential of which is opposite to that of the point to which the grid of tube 7 is connected. The capacity 9, internal capacity 10 of the amplifier tube and inductances 3 and 4 may 15 be considered to comprise a Wheatstone bridge. Load L is connected across two opposite corners of this Wheatstone bridge while the condenser 2, in the frequency determining circuit of the oscillator, is connected across the other two opposite corners. Under these conditions when the capacity of 20 condenser 9 is adjusted to have the same ratio to the internal capacity of tube 7 as the inductance of coil 4 bears to the inductance 25 of coil 3, at a given frequency, the bridge will be in a state of equilibrium at that frequency with respect to tube 7 as a generator. In this condition currents flowing in branches 30 3 and 4 from tube 7 as a source will be equal and opposite in direction whereby the effect of these currents on the oscillation circuit as a whole will be neutralized. The same explanation may be referred to Fig. 2 by substituting condensers 13 and 14 for inductances 3 and 4 and inductance 15 for condenser 2.

It has heretofore, in many cases, been unsatisfactory in oscillation generation systems to employ a single tuned circuit to establish 40 the frequency of oscillations generated and to couple the oscillation generator to an amplifier tube, due to the variation in the frequency of the oscillations as the impedance of the load is varied. By employing the means herein described such variation is substantially prevented.

This invention is particularly useful in transmitting apparatus where it is desirable 50 to have substantially constant frequency during variation of the impedance of the load to which the oscillations are applied. Maintenance of constant frequency is essential in cases where transmitting channels are 55 relatively close together in frequency, and slight variations in carrier frequency would be sufficient to cause interference with other carrier waves and produce objectionable beats in the receiver. An incidental advantage of this arrangement is that singing of the amplifier circuit due to the internal grid-plate capacity 10 of amplifier tube 7 is prevented.

Any other well known method of neutralizing 60 the coupling effect of the plate-grid ca-

pacity of the amplifier tube may be employed in place of the method herein described if desired.

Although this system has been shown and described as applied to particular circuits 70 and uses, it is not to be limited thereto but only in accordance with the invention as defined in the following claims.

What is claimed is:

1. An electrical system comprising two 75 three-electrode space discharge devices and a tuned circuit having a two-part inductance, one device having its electrodes connected to different potential points on said tuned circuit and cooperating therewith to constitute an oscillator, connections whereby oscillations are supplied from said tuned circuit to the second device, and a connection from one of the electrodes of the second device through a condenser to one terminal of 80 one part of said inductance to effect neutralization of the interelectrode capacity of said second device.

2. In an electrical system, an oscillator comprising a space discharge device having 85 input and output circuits coupled by a frequency determining circuit including an inductance comprising a plurality of sections, a three-electrode space discharge amplifier associated with a variable load, means for connecting electrodes of said amplifier to one inductance section, and means for connecting the other electrode of said amplifier through a capacity to said other inductance section.

3. In an electrical system, an oscillator 100 comprising a space discharge device having input and output circuits coupled by a frequency determining circuit including an inductance comprising a plurality of sections, a three-electrode space discharge amplifier 105 associated with a variable load, means for directly connecting certain electrodes of said amplifier to one inductance section, and means including a condenser for connecting another electrode of said amplifier to said other inductance section.

4. In a system, an oscillation generator comprising a three-element space discharge device, a frequency determining circuit operatively associated therewith, a three-electrode 115 space discharge amplifier, means directly connecting said frequency determining circuit to certain electrodes of the amplifier, a variable impedance load, means connecting said load to certain electrodes of said amplifier, and a variable condenser connecting the anode of said amplifier with a point in said frequency determining circuit of opposite high frequency potential from the point to which the grid of said amplifier is connected.

5. A wave transfer system including a space discharge oscillation generator, a tuned circuit comprising two impedances of like sign and an impedance of opposite sign for determining the frequency of oscillations 130

produced by said generator, a space discharge amplifier having input and output terminals, means directly connecting said input terminals across one of said impedances of like sign, a variable impedance load, means connecting said load across said output terminals, and a balancing condenser connecting the output circuit of said amplifier to the other of said impedances of like sign.

6. In a circuit including a source of high frequency oscillations, an amplifier therefor and a load circuit, means comprising a tuned circuit for governing the frequency of the oscillations and for coupling the oscillation generator to the amplifier, and means comprising an impedance element directly connected in energy flow relation between the load circuit and the tuned circuit for pre-

venting the impedance of the load circuit from effecting the frequency of said oscillations.

7. In a space discharge system, a source of high frequency oscillations, a space discharge amplifier having inherent capacity, means for coupling said source to said amplifier, a variable impedance load connected to said amplifier, a tuned circuit including said coupling means as a unit for establishing the frequency of said oscillations, and a balancing condenser directly connected between said load and said tuned circuit to prevent variations in load impedance from altering the frequency of said oscillations.

In witness whereof, I hereunto subscribe my name this 20th day of April, A. D., 1925.

JOHN F. FARRINGTON.
